[57] CLAIM

The ornamental design for a buoy marker launcher, as shown.

DESCRIPTION

FIG. 1 is a perspective view of a buoy marker launcher showing my new design;

FIG. 2 is a top plan view thereof;

FIG. 3 is a side elevation view thereof;

FIG. 4 is a side elevation view of the side opposite that shown in FIG. 3 thereof; and

FIG. 5 is a bottom plan view thereof.

The control box shown in FIG. 1 is not shown in FIGS. 2 thru 5 for ease of illustration.
